[57] CLAIM

The ornamental design for a stool, as shown and described.

DESCRIPTION

FIG. 1 is a perspective view from the front and side of stool in the form of an ottoman or footstool, showing my new design (the rear and opposite side views being mirror images of the front and side shown).

FIG. 2 is a side elevational view thereof.

FIG. 3 is a view in top plan of the stool of FIG. 1.
